The ornamental design for a clip-style light, as shown and described.

DESCRIPTION

FIG. 1 is a perspective view of a clip-style light showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line immediately adjacent to the shaded area represents unclaimed boundaries of the design. The broken line near the disclaimed neck represents an unclaimed parting line. The broken line showing of the remainder of the clip-style light is for environmental purposes only and forms no part of the claimed design.
